STRIKE PLATE

Carl I. Snyder, Marshallville, Ohio, assignor to
 Weather-Seal, Inc., Barberton, Ohio, a corporation of Ohio

Application March 17, 1949, Serial No. 81,881

1 Claim. (Cl. 292—340)

1

This invention relates to strike plates, more particularly adapted for use with the door latches of storm doors or closet doors, but which may be utilized with other doors, such as vehicle doors.

In the conventional strike plate now in general use in which provision is made for engagement with a spring latch bolt having a beveled nose, the tongue of the plate is beveled or rounded to more readily permit passage of the bolt across the plate, and a single opening is provided to receive the bolt and hold it in latching position. With this construction, when it becomes necessary to slam or quickly close a door, such as a storm door or a closet door, such door will frequently not close completely and the bolt will merely strike the beveled tongue of the plate and remain there, or move a short distance across the plate without reaching the opening in the plate that is intended to receive the bolt. Hence, such door may readily be blown open or otherwise opened when it is not intended to be.

It is an object of this invention to provide a strike plate that will permit a door to be slammed against air or other pressure and yet will hold the latch bolt in such position that the door cannot be opened without retracting the bolt.

Another object is to provide a strike plate that has a second opening in front of the usual opening, arranged just past the beveled end of the tongue with the front edge of the second opening extending slightly beyond the front edge of the doorjamb, so that when the latch bolt passes over the bevel of the tongue it will be forced into this second opening and remain there until the bolt is retracted to release it.

A further object is to provide a modified form of strike plate wherein the metal which is cut out of the plate to form the second opening is not entirely removed from the plate, but is bent toward the doorjamb, so that when a carpenter installs the strike plate on a doorjamb he will have to provide a recess in the doorjamb to receive this bent portion of the plate, which latter opening will thus be properly aligned with the second opening in the plate.

A further object is to provide an improved strike plate which is easy to manufacture, and which may be readily and quickly installed.

Other objects and advantages will become apparent from the following description taken in conjunction with the accompanying drawing.

In the drawing:

Fig. 1 is a horizontal section through one form of my strike plate showing adjacent parts in elevation,

2

Fig. 2 is a similar view through another form of my strike plate,

Fig. 3 is a perspective view of the strike plate shown in Fig. 1, and

Fig. 4 is a perspective view of the strike plate shown in Fig. 2.

Referring to the drawing and particularly to Figs. 2 and 4, the numeral 10 indicates a strike plate having a conventional latch bolt receiving opening 11 formed therein, with the free end of its tongue 12 beveled or rounded as at 13 in the usual manner, and with screw receiving openings 14 formed therein. The described construction constitutes the form of strike plate now in general use.

To the above described construction, I provide the plate 10 with a second latch bolt receiving opening 15 which is located between the opening 11 and the beveled end 13 of the tongue 12. The opening 15 is in horizontal alignment with the opening 11 and is smaller than the latter opening, but is still of sufficient size to receive the beveled end of a latch bolt.

Fig. 2 shows the strike plate 10 secured to a doorjamb 16 by means of screws 17 or the like, with the rounded end 13 of the tongue projecting past the front edge of the doorjamb a sufficient distance to permit the front edge of opening 15 to extend slightly past the front edge of the doorjamb. The doorjamb is provided in this instance with an enlarged recess 18 in alignment with the openings 11 and 15 in the plate, and of sufficient depth to receive a latch bolt when it extends into either of the openings 11 or 15. A portion of a beveled end, spring-pressed latch bolt 19, carried in a door 20, is shown in full lines in latching position with the beveled end of the bolt extending through the opening 11 in the plate and into the doorjamb recess 18. This full line position of the bolt 19 is the normal position of the bolt when the door 20 is fully closed, as will be understood.

As is well known, it is practically impossible to slam or quickly close a conventional closet door or storm door, due to the air pressure opposing the movement of the door. Thus, while many people attempt to close a door in this manner, they seldom succeed in moving the latch bolt past the rounded end of the tongue on the strike plate. With my construction, however, the front end of the opening 15 extends beyond the front edge of the doorjamb so that enough air is permitted to escape through opening 15 to allow the beveled end of the latch bolt to pass over the tongue of the plate and be forced into the opening 15 by the bolt spring. Thus,

with my arrangement, while the door is not fully closed when the latch bolt is in opening 15, nevertheless the door cannot be opened without retracting the bolt and removing the latter from opening 15. The position of the latch bolt 19 in opening 15 is clearly shown in broken lines in Fig. 2. After the bolt has become engaged in opening 15, if it is desired to fully close the door, this may be readily done by merely pushing on the door to force the bolt out of opening 15 into opening 11, and for the purpose of assisting the beveled end of the bolt in passing from opening 15 to opening 11, the edge of the metal at the rear of the opening 15 is beveled, as indicated at 21.

In Figs. 1 and 3, I have shown a modified form of strike plate 10' having the conventional latch bolt receiving opening 11', tongue 12', rounded edge 13', screw receiving openings 14' and the second latch bolt receiving opening 15', all similar to their unprimed counterparts in Figs. 2 and 4. In the modified form, however, the metal which is cut out of plate 10' in order to form the opening 15' is not completely removed from the plate, but is cut so that it may be bent in the direction of the doorjamb to provide an integral extension 22 on the plate which is spaced from the opening 15' and which is inclined or beveled as indicated at 23.

When the plate 10' is secured to a doorjamb 16', as by screws 17', with the doorjamb having an elongated recess 18' therein similar to the recess 18 in doorjamb 16, it will appear as in Fig. 1 with the extension 22 extending in the recess 18'. The action of the latch bolt 19' of the door 20' with respect to openings 15' and 11' is shown in Fig. 1. When the door 20' is slammed or quickly closed, the bolt 19' is received in the opening 15' as indicated in broken lines, and when fully closed the bolt is received in opening 11' as indicated in solid lines. When pushing the door from its broken line position to its solid line position, the inclined or beveled area 23 on extension 22 assists the beveled end of the latch bolt in passing out of opening 15' into opening 11'. Thus, the action of the latch bolt is the same when using either of the strike plates 10 or 10'.

The extension 22 on plate 10' also serves an additional purpose. In new door constructions it is an easy matter to cut a single recess in the doorjamb large enough to be in alignment with both latch bolt receiving openings in the strike plate, and either plate 10 or 10' may be readily used. But in old constructions where an old type conventional strike plate is being replaced by one of my new type plates, it is usually found that the doorjamb has but one recess therein which is opposite the single bolt receiving open-

ing in the old type plate. Such recess obviously must be enlarged or a second recess must be formed in the doorjamb opposite to the second bolt receiving opening in my plate, in order that the bolt may properly be received in such second opening. However, with some carpenters there is a tendency to replace the old plate with my plate 10, without forming any recess in the doorjamb in alignment with the opening 15, so that in such cases the device will not function properly due to the inability of the bolt to project far enough through opening 15 to become engaged therein. Thus, in making replacements of the nature mentioned, or for that matter with new constructions also, when my strike plate 10' is used, it is impossible to install the latter on a doorjamb without providing a recess in the doorjamb in alignment with opening 15', because the extension 22 will not permit the plate 10' to lie flush with the doorjamb unless a recess is provided in the latter to receive the extension.

While I have illustrated and described the preferred embodiments of my invention, it will be apparent that the invention is not limited thereto, and changes and modifications may be made therein without departing from the spirit of the invention or from the scope of the subjoined claim.

What is claimed is:

A strike plate for a door latch comprising a flat plate having a medial opening to receive a latch, an apron extending from one side of said plate, and having an outer edge curved out of the plane of said plate, said apron having a struck portion bent out of the plane of said plate on the same side thereof as said curved edge to provide an auxiliary opening between said medial opening and said curved edge, and the end of said struck portion being reversely bent to provide a terminal area generally parallel to the plane of said plate.
